UNITED STATES PATENT OFFICE.

ROY P. HIXSON, OF EAST LANSDOWNE, PENNSYLVANIA.

BINDER DEVICE.

1,257,001.

Specification of Letters Patent. Patented Feb. 19, 1918.

Application filed December 13, 1916. Serial No. 136,653.

To all whom it may concern:

Be it known that I, ROY P. HIXSON, a citizen of the United States, residing at East Lansdowne, in the county of Delaware and State of Pennsylvania, have invented certain new and useful Improvements in Binder Devices of which the following is a specification.

My invention relates to improvements in binder devices of the loose leaf sort.

The introduction of what is known as machine posting in bookkeeping has necessitated the use of books consisting of loose leaves which may be removed at will, inserted in the typewriter, and returned. This style of bookkeeping has also introduced the method of making the customer's statement in the same process as posting the ledger, such statements remaining as leaves of the ledger until sent to customers. This style of bookkeeping demands, therefore, a binder normally similar to the usual ledger but which may be rapidly taken apart in such wise as to release the leaves for posting purposes and as rapidly to permit their reassembling. As the number of pages, combining often the statements of customers, varies greatly from time to time, such a mechanical binder must be adjustable to a large fluctuation of this nature. Furthermore in order to same time in the use of such a loose leaf ledger it is important that it be supported when open in the position most convenient for removing the pages and that means be provided to maintain the removed pages in alinement immediately prior to returning them to the binder.

A great defect in loose leaf binders heretofore has been that in those devices where the loose leaves are held in place by closed holes, upon sectional posts, the leaves are inconvenient to remove and to return to place; whereas in those devices in which the loose leaves are held in place through notched or slotted holes upon posts, by means of the compression of the front and back binder-covers, a more or less complex mechanism is necessary to exert adequate pressure upon the loose leaves by the binder covers.

Among the objects of my invention, therefore, is to provide a binder from which loose leaves may be removed and returned more rapidly than heretofore. I intend, furthermore, to provide a binder device eliminating the use of compression to hold the loose leaves securely in place when the binder is

closed, yet allowing the leaves to be removed and returned with great ease through notched holes when the binder has been taken apart. I also aim to provide by my invention a posting cabinet adapted to support my loose leaf binder in the most advantageous position for taking it apart and removing the leaves and to provide a sure and simple means of reassembling the leaves in perfect alinement prior to replacing them in the binder after posting.

I attain these objects by a removable central post, passing through closed holes in the loose leaves, in conjunction with fixed sectional posts, serving to support the loose leaves in alinement upon notched holes; and by the use of a posting stand, combining the proper support for the ledger when in open position, and a section for receiving the leaves after postings are made and maintaining them in perfect alinement so that they may be readily returned to the binder.

Referring to the drawings, which represent merely by way of example suitable embodiments of my invention, Figure 1 is a side view of a loose leaf binder embodying my invention, in closed position, resting upon my posting stand; Fig. 2 is a plan view of my posting stand; Fig. 3 is a sectional view along the line 3—3 of Fig. 2, showing the central post partly withdrawn; Fig. 4 is a sectional view along the line 4—4 of Fig. 1, the central post having been removed, showing the loose leaves, resting in alinement upon the side posts through notched holes, the side posts supported in turn by cleats in the floor of the posting stand; Fig. 5 is the same sectional view with the central post screwed into place, locking the loose leaves, and showing by dotted lines the top binder-cover in place for locking the binder; Fig. 6 is a view of the back of the ledger showing the pages resting upon the side posts through notched holes and locked by the central post, passing through closed holes; Fig. 7 is a sectional view of the locking device of the top binder-cover.

Referring now with greater particularity to the said figures, where similar numerals refer to similar parts throughout:

The posting stand 1 constitutes the support of my loose leaf binder and 2 and 2¹ are respectively the bottom and top covers of the binder. The said covers contain the metal binding elements 5 and 5¹. The sectional posts 6 are permanently secured in

the binding element 5, and the post 7 is removably secured to the same binding element 5, between the posts 6, by means of a screw-threaded end. The top binder-cover 5² is provided with the holes 8, passing through the binder element 5¹, so spaced as to receive the two side posts 6, and with the hole 9 so spaced as to receive the center post 7. The ledger leaves are provided with 10 similarly spaced closed holes, to accommodate the post 7, and notched holes to accommodate the posts 6. The top binder element 5¹ contains a locking device such as I have illustrated in Fig. 7. In this locking device 15 the bar 10, containing elongated holes 11, so spaced as to receive the posts 6 and 7, is movable laterally in the space 12¹, within the binder element 5¹, by the threaded-screw 13'. The screw 13' engages the binder element 5¹ and is turned by the key 14'. When 20 the screw 13' is turned inwardly, the bar 10 is moved into binding contact, at its holes 11, with the posts 6 and 7, thereby locking the top binder-cover to the said posts at 25 any desired point, so that the ledger may be adjusted to contain any number of leaves. By turning the key in the reverse direction, the binding contact of the bar 10 is relieved, permitting the top binder-cover 30 to be easily slipped off the posts 6 and 7.

The posting stand 1 consists of side and end walls, and a floor, the floor being broken into two right angles. The first angle, consisting of the floors 12 and 13, receives the 35 ledger and maintains it in position for opening. For this reason the side 12 of the angle is tipped back from the perpendicular somewhat and the side 13 is tipped up a corresponding distance. The second angle, consisting of the floors 14 and 15, is set lower within the stand than the angle 12-13, while its floor 14 tips back farther than the floor 12. The side walls 16, which support the floors 12 and 13, extend to inclose the 40 angle formed by the floors 14 and 15, so forming a receptacle the width of which is such as just to receive the loose leaves 17 of the binder after posting and to maintain them in alinement so that they may be 45 readily returned to the binder. The side walls 16 may be conveniently cut away above the floor 15 in a manner to make the loose leaves accessible from the side, and the floor 15 may also be cut away (Fig. 2) 50 at its upper end to make the loose leaves accessible from below.

To the floor 13 of the posting stand are secured two cleats 18, spaced so as to receive the two posts 6 and allow the bottom binder element 5 to slip between them and the floor 12. The upper surfaces of the cleats 18 are made somewhat concave to receive the posts 6. The weight of the binder, when in position on these supports, falls partly upon the 55 floor 12 against which it lies, and chiefly

upon the cleats 18, being taken up through the posts 6. The said cleats are of such a height above the floor 13 as to give a slight clearance between the binder elements 5 and 5¹ and the floor 13 thereby taking the weight 70 of the ledger entirely off the binder elements 5 and 5¹. The binder is held securely in its position by the guides 19.

The manner of operating my loose leaf binder, by which I secure an improved method of opening the binder, removing and replacing the leaves and closing the binder again is as follows:

The binder is placed in position upon the posting stand, as illustrated in Fig. 1. The top binder-cover 2¹ is then removed from the posts 6 and 7 with great facility, the weight of the binder being taken up on the posts 6 and cleats 18. The binder-cover 2¹ once removed the pages are released by 80 unscrewing and drawing out the center post 7. The leaves now rest through their notched holes upon the posts 6 and may be be lifted off for posting or other purposes at pleasure, in any quantity, or from any 85 part of the ledger. After posting etc. the leaves are laid against the floor 15 where they are held in perfect alinement ready to be returned in any quantity or to any portion of the ledger by merely slipping their 90 notches over the posts 6. When the ledger is to be closed the center post 7 is passed through the closed holes of the pages and 95 screwed into the binder element 5. When the notched holes of the pages have been fitted to the posts 6, the pages will always be found in alinement to receive the post 7 through their closed holes. The top binder-cover 5¹ is now replaced by slipping it upon the posts 6 and 7 through its holes 8 and 9; 100 it is then locked by the key 14' after being brought into contact with the leaves of the ledger, no compression being required to hold the leaves in position, because of the 105 central locking post 7.

The permanently secured posts 6 are made sectional so as to be adjustable to any desired number of leaves, while several center posts of different lengths may be provided to meet similar requirements.

Having thus described my invention, what I claim as new and desire to secure by Letters Patent, is:

1. The combination of a binder consisting of two independent binding members, one provided with permanent posts for engaging loose pages through notches, and a removably attached post for locking the pages through closed holes, the other binding member being adjustable upon the said posts, with a posting stand comprising means to support and maintain the binder upon its said permanent posts and a receptacle of equal width with the pages for receiving removed pages.

2. In a binder device, the combination, with one binding member comprising two posts permanently attached thereto for engaging loose pages through notches, and a post removably attached thereto for locking the pages through closed holes, and the other binding member adapted to engage the said posts through holes and provided with a lock, of a posting stand having two parts, one part comprising a floor having two cleats secured thereto supporting the binder upon said permanently attached posts, the other part comprising a receptacle of equal width with the pages for receiving removed pages.
3. In a binder device, the combination, with one binding member comprising permanent posts for engaging leaf notches and a removable post for locking the leaves through closed holes, and a second binding member adjustable to the said posts, of a posting stand having two parts, one part comprising a floor having cleats secured thereto supporting the binder beneath said permanent posts, the other part comprising a receptacle of equal width with the pages for receiving removed pages.
4. The combination of a loose leaf ledger comprising two separate binding covers, the one provided with permanent posts and a removable post, the other adjustable to the said posts, with a posting stand comprising means to support and maintain the binder upon said permanent posts and a receptacle of equal width with the ledger leaves.
5. In a binder device, the combination, with one binding member comprising permanent posts and a removable post and the other binding member adjustable upon the said posts, of a posting stand comprising cleats secured to the floor thereof and supporting the binder beneath the said permanent posts.
6. The combination of a posting stand having two parts, one part comprising a floor having supporting cleats secured thereto, the other part a receptacle of equal width with the ledger leaves, with a binder comprising a separate bottom and top binding member, the bottom member provided with permanent posts resting upon the said supporting cleats, and a removable post, the top member adjustable upon the said posts.
7. In a loose leaf binder, the combination of a bottom binding member having permanent posts, notched pages engaging said permanent posts, a top binding member adjustable upon the said permanent posts through apertures, and a post which engages the said bottom binding member removably, the said notched pages through closed holes and the said top binding member through an aperture.
8. A loose leaf binder comprising a bottom binding member having permanent posts, notched pages engaging the said permanent posts, a top binding member adjustable upon the said permanent posts through apertures, and a central post engaging the bottom binding member removably, the said notched pages through closed holes, and the said top binding member through an aperture.

In witness whereof I do affix my signature in the presence of two witnesses.

R. P. HIXSON.
